To all whom it may concern:

Be it known that I, JEANNETTE SABIN, a citizen of the United States, residing at Coeur d'Alene, in the county of Kootenai and State of Idaho, have invented a new, original, and ornamental Design for a Badge, of which the following is a specification, reference being had to the accompanying drawing, forming a part thereof.

end of the ribbon is secured a small fragment of stone D and pending from the bow is the representation of a potato, the assembled features constituting a St. Patrick's souvenir comprising the pipe tied with a bow of green ribbon, and including a potato and a piece of the Blarney Stone.
